(57) **CLAIM**

The ornamental design for a power module, as shown and described.

DESCRIPTION

FIG. 1 shows a front perspective view of a power module showing our new design in an open configuration;

FIG. 2 shows a front view of the power module of FIG. 1; FIG. 3 shows a back view of the power module of FIG. 1; FIG. 4 shows a right view of the power module of FIG. 1; FIG. 5 shows a left view of the power module of FIG. 1; FIG. 6 shows a top view of the power module of FIG. 1; FIG. 7 shows a bottom view of the power module of FIG. 1; FIG. 8 shows a rear perspective view of the power module of FIG. 1;

FIG. 9 is a front perspective view of the power module of FIG. 1, shown in a closed position;

FIG. 10 shows a front view of the power module of FIG. 9; FIG. 11 shows a back view of the power module of FIG. 9; FIG. 12 shows a right view of the power module of FIG. 9; FIG. 13 shows a left view of the power module of FIG. 9; FIG. 14 shows a top view of the power module of FIG. 9; FIG. 15 shows a bottom view of the power module of FIG. 9; and,

FIG. 16 shows a rear perspective view of the power module of FIG. 9.

The broken lines illustrate environmental structure and form no part of the claimed design.

1 Claim, 12 Drawing Sheets
